REFRIGERATION EVAPORATOR

Lawrence C. Smith, Kenmore, N. Y., assignor to
Fedders Manufacturing Company, Inc., Buffalo, N. Y.

Application May 15, 1937, Serial No. 142,833

3 Claims. (Cl. 62—126)

This invention relates to electric refrigeration, and it has particular reference to a new and improved evaporator adapted for service in a domestic refrigerator operating on the compressor-condenser-expander circuit.

More particularly, the invention contemplates an evaporator adapted to receive volatile liquid refrigerant containing quantities of lubricating oil, so constructed as to require a minimum of 10 overhead clearance and space when placed in a domestic refrigerator, so that the box temperatures may be maintained at all points within desired ranges without undue reduction of the box capacity. The evaporator of the present invention also is designed to operate on the flooded principle, but with a smaller charge of refrigerating fluid than has heretofore been deemed necessary, without, however, sacrificing the area available for heat exchange purposes.

20 A preferred embodiment of the invention, achieving the foregoing objectives by means of a simple and inexpensive construction, will be described in the following portions of this specification, to be read in conjunction with the appended drawings, wherein:

Fig. 1 is a side elevation of the evaporator with portions of the suction header broken away to show the internal structure;

Fig. 2 is a front view thereof;

30 Fig. 3 is an enlarged fragmentary section on the line 3—3 of Fig. 2;

Fig. 4 is a top view of the refrigerated shelf; and

Fig. 5 is an enlarged fragmentary section on the line 5—5 of Fig. 1.

The evaporator includes cylindrical supply and suction headers 10 and 11, of small and large diameters respectively, which are horizontally disposed and connected to the terminals 12 and 13 respectively of each of a plurality of depending tubular ducts 14. The terminals 12 extend through holes 15 formed in the bottom of the header 10, and project upward to approximately the center thereof (Fig. 5). A hole 16 is drilled 40 in each feed terminal 12 at a point located immediately within the header. The terminals 13 project but a short distance within the header 11 through holes 17.

An inlet fitting 18 is secured to the rear end 50 of the header 10, and it is suitably connected to a tube 19 leading to a condenser or equivalent refrigerant supply source (not shown). A control device 20 of any known type is interposed in the supply tube 19 to control the volume of 55 refrigerant supplied to the header 10. The suc-

tion header 11 is capped at its rear extremity by a fitting 21 which communicates with a suction tube 22 through which the gaseous products of evaporation and returning oil are withdrawn from the evaporator. The front end of the header 11 receives a head 23. A perforated baffle tube 25 is concentrically disposed within the header 11 and its extremities are supported on projections 26, 27, formed on the fitting 21 and head 23 respectively. The tube 25 thus 10 divides the header into inner and outer chambers 28 and 29; the outer chamber, being in direct communication with the terminals 13, receives the full force of the relatively violent periodic discharges of the ducts, which is expended on the circular wall thereof. The communicating inner chamber 28 is thus fully protected, and the liquid therein remains in a tranquil state, subject only to variations in liquid level, as dictated by the rates of evaporation and 15 supply. A suction pipe 30 projects angularly from the fitting 21 and its open end is disposed at a high point in the inner chamber 28.

To prevent the displacement of liquid in the supply header 10 and adjoining portions of the 25 ducts 14 by gas volumes, an equalizing tube 31 is positioned in one of the ducts 14 with its terminals projecting to high points in both headers. Communication is thus established between the gas pockets at the top of the headers, and as a 30 result pressures are equalized and the liquid in the evaporator is permitted to assume natural gravitational levels. If necessary, several of the ducts may be supplied with equalizing tubes.

In applying the invention to domestic refrigerators, it is advantageous to form the ducts 14 of fairly large diameter tubing, and to flatten major portions transversely, as indicated by the numeral 32 (Fig. 3), so that larger areas of direct heat exchange surface are presented to the ambient air currents in the box in which the evaporator is mounted. Inasmuch as the flattening operation reduces the volumetric capacity of the ducts, it will be apparent that the benefits of the enlarged areas may be obtained 40 with but a relatively small charge of refrigerant in the system.

A rectilinear sleeve 33, forming a freezing compartment, is mounted within the looped portions of the ducts 14. The side and bottom walls of the sleeve are disposed in intimate thermal contact with the ducts and are secured thereto by soldering, as indicated by the numeral 34 (Fig. 3). The sleeve is provided with ice tray shelves, which are herein shown as of the plain and re- 45 50 55

frigerated types 35 and 36, respectively. The refrigerated shelf 36 has a loop 37 of flattened tubing soldered to its lower surface, with the terminals 38 and 39, which are not flattened, 5 projecting outward and upward for communication with the headers 10 and 11 respectively, in a similar manner to the ducts 14. The sleeve 33 is formed with notches 41 which receive the terminals 38 and 39 in assembly.

10 In operation, the liquid level in the evaporator is maintained by the controls at a normal point below the center of the supply header 10. The liquid is introduced into the ducts 14 through the small orifices 16 in the feed terminals 12, which 15 insures that each duct is supplied with substantially equal volumes of refrigerant at a steady rate. Inasmuch as the levels in the header 10 are reflected in the header 11, due to the pressure equalizing effects of the tube 31, it will be 20 observed that the headers are disposed so that even in extreme cases, where the level approaches the center of the inlet header (Fig. 5) the level is below the mouth of the suction pipe 30 in the header 11.

25 While the invention has been described in connection with a single embodiment, it will be understood that it is susceptible of numerous modifications and variations, and accordingly it should be construed as commensurate with the scope 30 of the following claims.

I claim:

1. A refrigeration evaporator comprising a pair of spaced headers disposed horizontally at substantially the same level, an ice tray sleeve disposed beneath the headers, a plurality of ducts 35 extending about the sides and bottom of the sleeve in thermal contact therewith, said ducts being flattened transversely of the sleeve, the

extremities of the ducts extending through the lower portions of both headers, the extremities entering one header being each formed with a small orifice adjacent the point of entry, a refrigerant supply conduit communicating with 5 said last named header and a suction conduit communicating with the remaining conduit.

2. A refrigeration evaporator comprising horizontally disposed tubular suction and inlet headers, said inlet header being of a substantially 10 smaller diameter than the suction header and being disposed at substantially the same level, a plurality of depending ducts having extremities extending through lower portions of both headers, the extremities entering the inlet header 15 extending upward to substantially the diametrical plane of the header, said extremities being each formed with a small orifice adjacent the point of entry in the inlet header, a refrigerant supply conduit communicating with the inlet 20 header and a suction conduit communicating with the suction header.

3. A refrigeration evaporator comprising horizontally disposed tubular inlet and outlet headers, a plurality of depending ducts having extremities extending through lower portions of both headers, the extremities entering the inlet header extending upward to substantially the diametrical plane of the header, said extremities being each formed with a small orifice adjacent 25 the point of entry in the inlet header, a small tube extending through one of the ducts and having terminal portions extending upward therethrough to a high point within each header, a refrigerant supply conduit communicating with 30 the inlet headers, and a suction conduit communicating with the suction header.

LAWRENCE C. SMITH.
